(57) **CLAIM**

We claim the ornamental design for a floor mount, as shown and described.

DESCRIPTION

FIG. 1 is a perspective view of the floor mount showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom view thereof;

FIG. 8 is a perspective view of another embodiment of floor mount showing our new design;

FIG. 9 is a front view of the floor mount in FIG. 8;

FIG. 10 is a rear view of the floor mount in FIG. 8;

FIG. 11 is a right side view of the floor mount in FIG. 8;

FIG. 12 is a left side view of the floor mount in FIG. 8;

FIG. 13 is a top plan view of the floor mount in FIG. 8; and,

FIG. 14 is a bottom view of the floor mount in FIG. 8.

The broken lines shown are for illustrative purposes only and form no part of the claimed design.

The broken line showing of portions of the floor mount in FIGS. 8-14 forms no part of the claimed design.
